UNITED STATES PATENT OFFICE.

BERNHARD JACQUES FLÜRSHEIM, OF FLEET, ENGLAND.

BRISANT EXPLOSIVE.

No Drawing. Application filed October 9, 1924, Serial No. 742,513, and in Great Britain October 28, 1923.

It is an object of my invention to produce an explosive destined for blasting or demolition operations which shall combine impenetrability by water with high shattering power, high density, reliable and easy detonation, safety in handling and reasonable cost. No explosive hitherto available fulfills all these requirements.

Thus amatols, which have been used under water in closed containers only, cannot be detonated at a density sufficiently high to ensure a great shattering effect. Liquid nitroglycerine—largely used, for the shooting of oil wells—involves high cost through the local manufacturing and specialized handling necessitated by its liability to accidental explosion and freezing, and causes frequent loss of life. Blasting gelatine, which has been used similarly, is often erratic in its detonation. Trinitrotoluene (T. N. T.) is weaker; besides, compressed T. N. T. is penetrated by liquids, and cast T. N. T. is too difficult to detonate. Compressed T. N. A. (Tetranitroaniline) is penetrated by water.

I have found that crystalline nitro-explosives which like T. N. A. cannot be conveniently fused but have the necessary qualities with the exception of imperviousness to water become impervious without detracting substantially from the other qualities when they are permeated by a proportion of a suitable fusible nitro-compound, of the necessary degree of insolubility in water, which has solidified in the mass, the proportion of this fusible nitro-compound being such that the mixture containing the fused compound cannot readily be poured when it is at a temperature which is only slightly higher than the temperature at which said fusible nitro-compound melts in the mass.

Thus it is possible to obtain completely water-proof T. N. A.-compositions of high density, capable of being easily moulded, when so small a percentage of the admixed fusible nitro-compound is used that the composition when heated as aforesaid cannot be poured readily; and that explosives thus obtained—using suitable fusible nitro-compounds—can be detonated with ease and regularity and possess a shattering power more closely approximating the outstanding briance of T. N. A.; and that they generally fulfil the requirements outlined above for an

explosive which may be used under water. 55

Other suitable materials, such as, for instance, one or more other suitable nitro-compounds or inorganic nitrates, may be embodied in such compositions.

Examples of explosive compositions made 60 in accordance with my invention are as follows:—

	Per cent.				
T. N. T.-----	5	30	23	10	9
Tetryl-----	0	0	0	0	3
T. N. A.-----	65	60	65	90	88
Barium nitrate-----	30	10	12	0	0

The minimum of fusible nitro-compound required varies according to the nature and proportions of the ingredients; it does not, for instance, exceed 5 per cent in the first example. 70

The compositions are obtained by causing the fused portion to be distributed throughout the unfused portion; this object may be attained by mixing the crystalline nitro-explosive which cannot conveniently be fused with the fusible nitro-compound and heating the mixture until the fusible compound is liquefied; or by melting the fusible nitro-compound and mixing with it the crystalline nitro-explosive which cannot conveniently be fused. 75

In the preferred procedure an intimate mixture (made for instance by grinding) of the materials is filled into a container which may be either a mould or the final container (where such is used), and the container is heated until the fusible nitro-compound is liquefied. If high density is desired, pressure may be applied before and/or during cooling. After the container has been cooled or allowed to cool, the composition is found to be hard, compact, of desired shape, impervious to water or mineral oil and, when desired, generally of a density approximating its absolute density (usually in the neighborhood of 1.9). 80

The compositions of which the above are examples offer special advantages for the "shooting" ("torpedoing") of oil wells; but they can also be used advantageously for many other purposes, such as military demolition work, or (with or without a container) for blasting operations under water, or for surface demolition of iron, rocks, trees, etc. 100

In the designation "a fusible nitro-com-

5 pound" used herein, I include a fusible mixture of nitro-compounds as well as a single fusible nitro-compound, and in the designation "a nitro-compound which cannot conveniently be fused" used herein, I include a mixture of such nitro-compounds as well as a single such nitro-compound.

10 Having thus fully described the nature of the said invention and the best means I know of carrying the same into practical effect, I claim:—

15 1. A process for producing an explosive composition impervious to water from a material consisting of a crystalline nitro-compound which cannot conveniently be fused which process consists in causing the material to be permeated by such a proportion of a fusible nitro-compound which has solidified in the mass that the mixture cannot readily be poured when it is at a temperature which is only slightly above the temperature at which this fusible compound melts in the mass.

20 2. A process for producing an explosive composition impervious to water from a material consisting of tetranitroaniline, which process consists in causing the material to be permeated by such a proportion of a fusible nitro-compound which has solidified in the mass that the mixture cannot readily be poured when it is at a temperature which is only slightly above the temperature at which said fusible compound melts in the mass.

25 3. A process for producing an explosive composition impervious to water from a material consisting of a crystalline nitro-compound which cannot conveniently be fused, which process consists in mixing with the material a fusible nitro-compound in such proportion that the mixture cannot readily be poured when it is at a temperature which is only slightly above the temperature at which said fusible compound melts in the mass, and then heating the mixture until the said fusible nitro-compound is fused.

30 4. A process for producing an explosive composition impervious to water from a material consisting of a crystalline nitro-compound which cannot conveniently be fused, which process consists in mixing with the material a fusible nitro-compound in fused state in such proportion that the mixture cannot readily be poured when it is at a temperature which is only slightly above the temperature at which said fusible nitro-compound melts in the mass.

35 5. A process for producing an explosive composition impervious to water from a material consisting of a crystalline nitro-compound which cannot conveniently be fused, which process consists in causing the material to be permeated with such a proportion of trinitrotoluene which has solidi-

fied in the mass that the mixture cannot readily be poured when it is at a temperature which is only slightly above the temperature at which the trinitrotoluene melts in the mass.

40 6. A process for producing an explosive composition impervious to water from a material consisting of a crystalline nitro-compound which cannot conveniently be fused, which process consists in mixing the material with such a proportion of trinitrotoluene that the mixture cannot readily be poured at a temperature which is only slightly above the temperature at which the trinitrotoluene melts in the mass and then heating the mixture until the trinitrotoluene fuses.

45 7. A process for producing an explosive composition impervious to water from a material consisting of a crystalline nitro-compound which cannot conveniently be fused, which process consists in mixing the material with such a proportion of fused trinitrotoluene that the mixture cannot readily be poured at a temperature which is only slightly above the temperature at which the trinitrotoluene melts in the mass.

50 8. A process for producing an explosive composition impervious to water from a material consisting of tetranitroaniline, which process consists in causing the material to be permeated with between 5 and 40 per cent by weight of trinitrotoluene which has solidified in the mass.

55 9. A process for producing an explosive composition impervious to water from a material consisting of tetranitroaniline, which process consists in causing the material to be permeated with between 10 and 28 per cent by weight of trinitrotoluene which has solidified in the mass.

60 10. An explosive composition which is impervious to water and contains a crystalline nitro-compound which cannot conveniently be fused, permeated with a fusible nitro-compound which has solidified in the mass, the composition being incapable of being readily poured when at a temperature which is only slightly above the temperature at which the said fusible nitro-compound melts in the mass.

65 11. An explosive composition impervious to water and containing tetranitroaniline permeated with a fusible nitro-compound which has solidified in the mass, the composition being incapable of being readily poured when at a temperature which is only slightly above the temperature at which the said fusible nitro-compound melts in the mass.

70 12. An explosive composition impervious to water and containing tetranitroaniline permeated with trinitrotoluene which has solidified in the mass, the composition being incapable of being readily poured when at

- a temperature which is only slightly above the temperature at which the trinitrotoluene melts in the mass.
13. An explosive composition containing 5 tetranitroaniline and trinitrotoluene, the trinitrotoluene amounting to between 5 and 40 per cent of the weight of the mixture.
14. An explosive composition containing 10 trinitrotoluene amounting to between 10 and 28 per cent of the weight of the mixture.
15. A process for producing an explosive composition impervious to water from a material comprising a crystalline nitro-compound which cannot conveniently be fused, which process consists in causing the material to be permeated by such a proportion of a fusible nitro-compound which has solidified in the mass that the mixture cannot 20 readily be poured when it is at a temperature which is only slightly above the temperature at which this fusible compound melts in the mass.
16. A process for producing an explosive 25 composition impervious to water from a material comprising tetranitroaniline, which process consists in causing the material to be permeated by such a proportion of a fusible nitro-compound which has solidified in the 30 mass that the mixture cannot readily be poured when it is at a temperature which is only slightly above the temperature at which said fusible compound melts in the mass.
17. A process for producing an explosive 35 composition impervious to water from a material comprising a crystalline nitro-compound which cannot conveniently be fused, which process consists in mixing with the 40 material a fusible nitro-compound in such proportion that the mixture cannot readily be poured when it is at a temperature which is only slightly above the temperature at which said fusible compound melts in the 45 mass, and then heating the mixture until the said fusible nitro-compound is fused.
18. A process for producing an explosive 50 composition impervious to water from a material comprising a crystalline nitro-compound which cannot conveniently be fused, which process consists in mixing with the 55 material a fusible nitro-compound in fused state in such proportion that the mixture cannot be readily be poured when it is at a temperature which is only slightly above the temperature at which said fusible nitro-compound melts in the mass.
19. A process for producing an explosive 60 composition impervious to water from a material comprising a crystalline nitro-compound which cannot conveniently be fused, which process consists in causing the material to be permeated with such a proportion of trinitrotoluene which has solidified in the 65 mass that the mixture cannot readily be poured when it is at a temperature which is only slightly above the temperature at which the trinitrotoluene melts in the mass.
20. A process for producing an explosive 70 composition impervious to water from a material comprising a crystalline nitro-compound which cannot conveniently be fused, which process consists in causing the material to be permeated with a fusible nitro-compound in fused state in such proportion that the mixture cannot readily be poured when it is at a temperature which is only slightly above the temperature at which this fusible nitro-compound melts in the mass and applying pressure prior to the solidification of said fusible compound.
21. A process for producing an explosive 75 composition impervious to water from a material comprising a crystalline nitro-compound which cannot conveniently be fused, which process consists in mixing the material with such a proportion of trinitrotoluene that the mixture cannot readily be poured at a temperature which is only slightly above the temperature at which the trinitrotoluene melts in the mass and then heating the mixture until the trinitrotoluene 80 fuses.
22. A process for producing an explosive 85 composition impervious to water from a material comprising a crystalline nitro-compound which cannot conveniently be fused, which process consists in mixing the material with such a proportion of fused trinitrotoluene that the mixture cannot readily be poured at a temperature which is only slightly above the temperature at which the trinitrotoluene melts in the mass.
23. A process for producing an explosive 90 composition impervious to water from a material comprising a crystalline nitro-compound which cannot conveniently be fused, which process consists in causing the material to be permeated with such a proportion of fused trinitrotoluene that the mixture cannot readily be poured at a temperature which is only slightly above the temperature at which the trinitrotoluene 95 melts in the mass.
24. A process for producing an explosive 100 composition impervious to water from a material comprising tetranitroaniline, which process consists in causing the material to be permeated with such a proportion of fused trinitrotoluene that the mixture cannot readily be poured when it is at a temperature which is only slightly above the temperature at which the trinitrotoluene 105 melts in the mass.
25. A process for producing an explosive 110 composition impervious to water from a material comprising tetranitroaniline, which process consists in causing the material to be permeated with between 5 and 40 per cent by weight of trinitrotoluene which has solidified in the mass.

In testimony whereof I have signed my name to this specification.

BERNHARD JACQUES FLURSCHEIM.
